UNITED STATES PATENT OFFICE.

EUGENE H. TAYLOR, DECEASED, LATE OF BOSTON, MASSACHUSETTS, BY GEORGE A. TAYLOR, ADMINISTRATOR, OF BOSTON, MASSACHUSETTS, ASSIGNOR TO JOHN T. ROBINSON COMPANY, OF BOSTON, MASSACHUSETTS, A CORPORATION OF MASSACHUSETTS.

LABEL-APPLYING MACHINE.

1,403,720.

Specification of Letters Patent. Patented Jan. 17, 1922.

Original application filed April 18, 1917, Serial No. 162,898. Divided and this application filed March 2, 1920. Serial No. 362,667.

To all whom it may concern:

Be it known that EUGENE H. TAYLOR, deceased, late of Boston, county of Suffolk, Commonwealth of Massachusetts, invented 5 a certain new and useful Improvement in Label-Applying Machines, of which the following is a specification, reference being had therein to the accompanying drawings.

This application is a division of the application Serial No. 162,898, filed April 18, 10 1917, by Eugene H. Taylor, deceased.

This invention has for its object label transferring mechanism for use in a machine for applying labels, particularly end 15 labels, to set-up boxes, such as shoe boxes, shirt boxes, collar boxes, and the like.

While the invention is shown and described as adapted for operation on paper boxes, it will be understood that it may be 20 employed as part of a machine for applying labels to metallic boxes or, in fact, to any boxes of rectangular shape.

In the labeling machine, a portion of which is shown in the accompanying drawings, 25 the labels are placed in a floating hopper or reservoir and the glue or paste is put in a suitable pan. The top label is taken from the pile by automatic suction-operated mechanism, adhesive is applied to the label 30 and it is carried to the position where parts of the machine, not shown in the present application, apply the label to the box, roll it down and eject the finished box from the machine.

The invention described herein is capable 35 of a variety of uses and, therefore, only a single application of the invention is illustrated.

The invention will be fully understood 40 from the following description when taken in connection with the accompanying drawings, and the novel features will be pointed out and clearly defined in the claims at the close of this specification.

In the drawings, Fig. 1 is a front elevation 45 of a machine embodying the invention.

Fig. 2 is a side elevation of the mechanism embodying the invention.

Fig. 3 is a section on line 3, 3 of Figure 2.

The machine includes a floating label reservoir which will now be described. The 50 object of this floating label reservoir is to

maintain the top label of the pile of labels always at the same level, the bottom label occupying different positions as the pile of 55 labels varies in thickness. The labels are placed on a floating shelf 45 forming the bottom of the reservoir, the sides of which are formed by grate-shaped members which are laterally adjustable for different sizes of 60 labels, but do not move vertically. The floating shelf 45 is provided with bars 47 which project through the slots between the bars composing the grate-shaped sides 46 of the reservoir. This is to make it possible 65 to move the sides of the reservoir laterally to adjust them towards and away from each other for different sizes of labels and still maintain a complete support for the bottom 70 of the pile of labels. It also permits vertical movement of the bottom or shelf of the reservoir relatively to the sides to maintain the top label of the pile in the same position. The lateral adjustment of the sides 46 of the reservoir is accomplished by means of rods 75 11 and set screws 48 in brackets 49 on the frame of the machine.

The floating shelf 45 is secured by means of a head 50 to the upper end of a slide composed in part of a rod 51 carried by two 80 links 52. The links 52 are secured to the ends of two arms 53 fixed to a hub 54 which together with its arms forms a rocking lever. The hub 54 is on a stud shaft 55 which shaft also carries an arm 56 on which is a 85 weight or counterpoise 57 which, being adjustable lengthwise of the arm 56, exerts a force sufficient to hold the pile of labels yieldingly in the highest position permitted by a pair of stops 58 which engage the upper 90 rear corners of the pile of labels. This mechanism is such that the pile of labels is constantly raised as labels are taken from the top of the pile by the label-feeding mechanism. By this means, the top label 95 always occupies the same position with relation to the label-transferring mechanism.

The top label in the pile is lifted off the pile by one or more suction nozzles 59 connected to a header 60 in which suction is produced by a suction pump 61. The header 60 is connected with the pump by a flexible tube 62. The header 60 and attached suction nozzles 59 are movable vertically on a

parallel motion composed of two bars 63 mounted on pivots 64 on the frame of the machine. One of the bars 63 composing the parallel motion is actuated by an arm 65 having on its lower end a cam roll 66 engaging a cam 67 on a cam shaft 68. The cam shaft 68 is driven by a vertical shaft 12 which is itself driven by a cross shaft 13 operated by gears 14 and 15 the latter of 10 which is on the end of the shaft on which is mounted a glue roll 84.

The movement of the vacuum nozzles is relatively small. The nozzles move periodically down into contact with the upper surface of the top label and then upward again, each time lifting the top label slightly away from the remainder of the pile.

At 69 is shown a large picker roll which is constantly revolving, being geared to the 20 cam shaft 68, already described. At each end of the picker roll 69 is a spider 70. One arm 71 of the spider supports a small movable picker roll 72, another arm carries a spreader arm 73 across the front of the large 25 picker roll and a third arm 74 carries a cam roll 75 which engages a cam 16 on the cam shaft 68. The movements of the parts are timed so that, just after the top label has been lifted up by the vacuum nozzles as described, 30 the small picker roll 72 is oscillated backward about the axis of the large picker roll 69 by means of the cam 16 and the arm 74, thereby causing the two picker rolls to seize between them the end of the label lifted from 35 the pile by the nozzles. The small picker roll is positively driven from the large picker roll by means of a pair of intermeshing gears 77 and 78 so that the two rolls have the same surface speed.

40 The label is delivered by the picker rolls 69 and 72 on to a series of transfer belts 76 running about the pulleys 79 and 80. The pulley 79 is actuated by gears 17 and 18 the former of which is on the shaft on which the 45 large picker roll is mounted. The transfer belt carries the label rearwardly and delivers it to the gluing mechanism. This gluing mechanism forms no part of the present invention, and being fully described in the application of Eugene H. Taylor, deceased,

previously referred to, will not be described in detail herein.

The floating shelf 45 which forms the bottom of the reservoir is inclined and slopes as shown in Figure 2 so that the pair of 55 picker rolls which takes the label from the suction nozzles and then delivers it to the transfer belt, operates with greater certainty since the label is moving downwardly all the time.

60

What is claimed is,

1. In a machine of the character described, a label reservoir having a bottom composed of a plurality of projecting bars, adjustable sides composed of gridiron shaped members 65 through the interstices of which said bars project to permit the sides to be adjusted toward and away from the centre.

2. In a machine of the character described, the improved label reservoir comprising a 70 bottom composed of projecting bars, a floating support for said bottom, sides for the reservoir composed of gridiron shaped members through the interstices of which said bars project whereby the said sides may be 75 moved toward and away from each other, and the said bottom may be moved vertically as the supply of labels in the reservoir varies.

3. In a machine of the character described, a positively rotating large picker roll, a 80 small picker roll supported adjacent said large picker roll and having the same peripheral speed, and mechanism to cause the small picker roll to travel bodily around the periphery of the large picker roll for a short 85 distance to receive a label.

4. In a machine of the character described, and in combination with a reservoir, suction nozzles to remove the top label from the reservoir, a pair of positively driven picker 90 rolls, and mechanism to cause one of the said picker rolls to move bodily about the axis of the other of said picker rolls to cause it to seize the label which had been removed from the label reservoir by the suction nozzles.

95

In testimony whereof I affix my signature.
GEORGE A. TAYLOR,
Administrator of the estate of Eugene H. Taylor, deceased.
